The ornamental design for a highway delineator guidepost, as shown and described.

DESCRIPTION

FIG. 1 is a reduced perspective view of a highway delineator guidepost showing my new design;

FIG. 2 is a top plan view thereof;

FIG. 3 is a bottom plan view thereof;

FIG. 4 is an enlarged side elevational view thereof, with the center away for ease illustration;

FIG. 5 is an enlarged rear elevational view thereof, with the center broken away for ease of center illustration.

FIG. 1

FIG. 2

FIG. 3

FIG. 4

FIG. 5
